(57) **CLAIM**

Thr ornamental design for a “portable communication device”, as shown and described.

DESCRIPTION

FIG. 1 is a front elevational view of a “portable communication device” showing our new design;

FIG. 2 is a rear elevational view thereof;

FIG. 3 is a left side elevational view thereof;

FIG. 4 is a right side elevational view thereof;

FIG. 5 is a bottom elevational view thereof;

FIG. 6; is a top plan view thereof; and,

FIG. 7 is a bottom, right and front perspective view thereof.

The broken line showings throughout the views are for illustrative purposes only and forms no part of the claimed design.
